UNITED STATES PATENT OFFICE.

GEORGE REHFUSS, JOHN GEORGE REHFUSS, AND MARTIN O. REHFUSS, OF PHILADELPHIA, PENNSYLVANIA, ASSIGNORS TO THE JOLY STOPPER COMPANY, OF SAME PLACE.

BOTTLE-STOPPER.

SPECIFICATION forming part of Letters Patent No. 402,350, dated April 30, 1889.

Application filed February 8, 1889. Serial No. 299,134. (No model.)

To all whom it may concern:

Be it known that we, GEORGE REHFUSS, JOHN GEORGE REHFUSS, and MARTIN O. REHFUSS, all citizens of the United States, and residents of Philadelphia, Pennsylvania, have invented certain Improvements in Bottle-Stoppers, of which the following is a specification.

Our invention relates to that class of bottle-stoppers in which the stopper is carried by a bail and said bail is acted upon by a cam-lever for the purpose of effecting the stoppering of the bottle, the object of our invention being to simplify and cheapen the construction of the operating devices for the stopper. This object we attain in the manner hereinafter set forth, reference being had to the accompanying drawings, in which—

Figure 1 is a side view of a bottle provided with a stopper and operating devices therefor, constructed in accordance with our invention, the bottle being sealed. Fig. 2 is a side view illustrating the position assumed by the parts on opening the bottle. Fig. 3 is a side view 25 showing the bottle fully opened. Fig. 4 is a perspective view of the stopper and its operating devices detached from the bottle. Fig. 5 is a view looking in the direction of the arrow, Fig. 1, with the stopper and part of the bottle-neck in section; and Figs. 6 and 7 are views showing modifications.

A represents part of the neck of the bottle, which has the usual enlarged head, forming a shoulder, *a*, some distance below the mouth.

The stopper consists of upper and lower disks, *b* *b'*, connected by a central shank, and between these two disks is the sealing-washer *d*, of rubber or equivalent material, the upper disk, *b*, being of such diameter that it can enter the mouth of the bottle to a point some distance below the upper edge of said mouth, the sealing of the bottle being effected by the compression of the projecting edges of the washer *d* between the periphery of said disk *b* and the inner wall of the bottle-mouth, some distance below the top of the same, as shown in Fig. 5, the purpose and advantages of this construction being set forth in a separate application filed by us and bearing even date herewith, and serially numbered 299,133.

The upper disk, *b*, of the stopper has a projecting stud, *f*, to which is secured the upper or transverse bar of the bail *B*, the opposite legs of the latter being bent inward at their lower ends, and these ends being adapted to 55 eyes *g*, formed upon the opposite side bars, *h*, of the operating-lever *D*. The upper ends of these arms *h* are connected together by a yoke, *i*, passing around one side of the neck of the bottle, and their lower ends are connected by 60 a yoke, *m*, passing around the other side of said neck, and, by preference, provided with a projecting loop, *n*, whereby the manipulation of the lever is facilitated. When the yoke *m* of the lever *D* is depressed, the upper ends 65 of the side bars, *h*, of the lever are caused to bear against the shoulder *a* of the bottle-neck, and the eyes *g* are forced downward, carrying with them the side legs of the bail *B*, and thus forcing the stopper firmly into the mouth of 70 the bottle, as shown in Figs. 1 and 5, undue movement of the operating-lever being prevented by contact of the yokes *i* and *m* with the sides of the bottle-neck. On elevating the yoke *m* of the operating-lever the upper ends 75 of the side bars, *h*, of said lever are moved from under the shoulders *a*, and the eyes *g* are at liberty to rise with the bail *B* until the stopper is free from the mouth of the bottle, as shown in Fig. 2, said stopper being then at 80 liberty to move outward and downward to the position shown in Fig. 3, so that the mouth of the bottle is completely unobstructed.

It will be observed that in our improved stopper the usual neck wire or band extending around the bottle below the mouth is dispensed with; hence the cost of the stopper is reduced, and it can be fitted to the bottle-neck more readily than if the neck wire or band were employed.

The operating-lever *D* (shown in Figs. 1 to 5) is made of a single piece of wire bent to the proper shape, the ends of the wire forming a butt-joint at the center of the yoke *i*. The ends of the wire may, however, form a lock-joint, if desired—as shown in Fig. 6, for instance—and a button, *n'*, may in some instances replace the loop *n*, as shown in Fig. 7. Although the form of stopper shown is preferred, it will be evident that our improved 95 100

operating devices may be used in connection with cap-stoppers of any of the usual forms. We are aware that in the patent of Prescott, No. 201,891, April 2, 1878, there is shown a stopper having a bail to the lower ends of which is hung a tightening-lever, said lower ends of the bail being guided in vertical grooves in a band around the neck of the bottle and the opposite arms of the tightening-lever acting on horizontal ribs or flanges projecting laterally from said band above the grooves, and we are also aware that in the specification of said patent it is suggested that the vertical grooves can be formed directly in and the lateral projections directly on the bottle; but such special construction of the bottle is rendered unnecessary in our case, and the operating mechanism for the stopper is much more compact than that shown in the Prescott patent, for the opposite arms of the tightening-lever are not, as in said patented stopper, set off from the neck by reason of the vertical guides for the lower ends of the bail, but lie close to the sides of the neck and engage with the shoulder formed by the usual head of the bottle, instead of with special projecting flanges, such as proposed by Prescott.

We therefore claim as our invention and desire to secure by Letters Patent—

1. The combination of the bottle with the stopper, the bail, and a tightening-lever hung to the bail and movable vertically on the bottle, the side bars of said lever occupying a position close to the sides of the neck and engaging with the shoulder formed by the head of the bottle, substantially as specified.

2. The combination of the shouldered bottle, the stopper, and the stopper-carrying bail, with the operating-lever hung to said bail and having opposite side bars for engaging with the shoulder of the bottle, and opposite yokes connecting the upper and lower ends of said side bars, substantially as specified.

In testimony whereof we have signed our names to this specification in the presence of two subscribing witnesses.

GEORGE REHFUSS.
